DESIGN FOR A TEMPLATE

Harold M. Alt, Jamaica, N. Y., assignor to American Locomotive Company, New York, N. Y., a corporation of New York

Application April 27, 1942, Serial No. 106,723

Term of patent 14 years

To all whom it may concern:

Be it known that I, Harold M. Alt, a citizen of the United States and a resident of Jamaica, in the county of Queens, city of New York, and State of New York, have invented a new, original, and ornamental Design for a Template, of which the following is a specification, reference being had to the accompanying drawing, which forms a part thereof.

The figure is a plan view of a template showing my new design.

The article is of conventional thickness.

I claim:

The ornamental design for a template, substantially as shown and described.

HAROLD M. ALT.
